UNITED STATES PATENT OFFICE.

CLAUDE L. POST, OF CHICAGO, ILLINOIS.

STOP SIGNAL.

Application filed October 2, 1922. Serial No. 591,874.

My invention relates to improvements in stop signals, and more particularly to a signal of the kind described which is simple, convenient, reliable, efficient and satisfactory for use wherever found applicable.

Another object of my invention is to provide a device of the kind described which will strikingly call the attention of a person in a car to the rear of that upon which the device is mounted to the fact that the forward car is stopping, and at approximately what speed said stopping or retardation in speed is taking place.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a plan view of my device as applied to a car;

Fig. 2 is a sectional view taken substantially on the line 2—2 of Fig. 1;

Fig. 3 is a sectional view taken substantially on the line 3—3 of Fig. 1;

Fig. 4 is a sectional view taken substantially on the line 4—4 of Fig. 1, and

Fig. 5 is a sectional view taken substantially on the line 5—5 of Fig. 1.

In the drawings, wherein I have illustrated the preferred embodiment of my invention, 1 indicates the frame or chassis of a car upon which my improved device is to be mounted, there being a propeller shaft or driving shaft 2 connected to the driving wheels (not shown) of said vehicle. 3 indicates a brake rod or lever, which is movable by hand or foot or otherwise, as desired, and 4 indicates a lamp or light adapted to be mounted upon the frame of the car, preferably at the rear end thereof, as shown. A lead wire 5 is connected to said lamp and at its other end is connected at 6 to a contact 7, the same being mounted upon any suitable part of the frame as for instance on a bracket 8, as shown and insulated from the frame. A contact member 9 is adjustably carried upon the brake rod 3, being insulated therefrom, and is adapted to contactingly engage the contact piece 7, as shown in Fig. 3. A

lead wire 10 is connected to the part 9, and is in turn connected to a battery or other source of power 11, which is preferably carried on any suitable part of the car, as at 13.

If desired, a switch 12 may be interposed at any point as at 12, and an indicator 22 may also be interposed in the circuit, so that one may tell whether or not the circuit is in good order and working properly. Adjustably secured upon the propeller shaft 2 and insulated therefrom is a cam member 14, having an arcuate peripheral surface 15 broken or interrupted at any suitable point, as at 16.

An arm 17 is secured to the rod 3, so as to be moved thereby whenever said rod is actuated, said member 17 being insulated from said brake rod. Contacts 18 and 19 are

spaced apart at the outer end of the member 17 and are insulated therefrom and from each other, said members 18 and 19 being

normally out of contact with the peripheral surface 15—16 of the member 14 when the brake rod is in its inoperative position, but

being moved into operative contact with said peripheral surface whenever the brake rod is actuated in the direction indicated by the arrow in Figs. 1 and 3. A wire 20 connects the contact 18 with the lead 5, and a wire 21 connects the contact 19 with the lead 10.

From the foregoing description it will be seen that whenever the brake rod is moved in the direction indicated by the arrows in Figs. 1 and 3 that the member 9 will break its contact with the member 7, putting out the light 4, and the contacts 18 and 19 will ride upon the peripheral surface of the member 14, keeping the light 4 on while said contacts are on the portion 15, but breaking the circuit and putting out said light when the contacts are at the portion 16. In other words,

there is a succession of "make and break" contacts, which causes the light to flicker. If the propeller shaft is rotating at a high rate

of speed when the brake is applied, it is evident that the signal 4 will correspondingly flicker at a high rate of speed and that as the speed of the shaft decreases the speed of flickering of the signal light will correspondingly decrease. Thus a driver to the rear of

the car upon which the signal is mounted may accurately determine the speed at which the car in front is being brought to a stop,

that is, if the speed of flickering is quickly retarded then the driver of the car behind knows that the car is being brought to a

quick stop, but if the speed of flickering

slowly decreases then the driver behind will know that the car in advance is being brought to a stop slowly or gradually and hence will govern his speed accordingly.

5 During the day the switch 12 may be turned off so that the lamp is lit only when the brake is applied, causing the light to flicker.

During the night the lamp may be used as an ordinary tail light by throwing in the 10 switch 12 and whenever the brake is applied the light will flicker.

It is apparent that the device shown may be used to operate the ordinary rear or tail lights in use, or if desired, a separate lamp 15 operable by my device may be used for the stop signal.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

25 28 What I claim as new and desire to secure by Letters Patent is:

1. In a device of the kind described and in combination, an electric signal mounted on a motor vehicle, a pair of circuits in parallel 30 to said signal, a rotary contact member in one of said circuits and drivingly connected to the drive shaft of the vehicle and having an interrupted contact surface, a stationary contact for the other circuit spaced from said 35 driven contact, and a pair of contacts carried by the brake rode of the vehicle and movable therewith between said spaced contacts, one of said pair of contacts engageable with said driven contact and the other engageable with 40 said stationary contact, whereby when said brake rod is actuated one of its pair of contacts will disengage from said stationary contacts to break the circuit thereof and the other will engage the interrupted contact face of 45 the driven contact to successively make and break the circuit controlled thereby.

2. In a self-propelled vehicle having a drive shaft and a braking mechanism, an electric signal, means for continuously supplying electric current to said signal, means 50 including a member mounted upon said driving shaft for intermittently supplying electrical current to said signal, and means including a member mounted upon said braking mechanism for simultaneously rendering said first-mentioned means functionally inoperative and for rendering said second means functionally operative.

3. In a self-propelled vehicle having a 55 driving shaft and braking mechanism, an

electric signal, means for continuously supplying electrical current to said signal, means including a cam mounted for rotation simultaneously with the rotation of the driving shaft for intermittently supplying electrical current to said signal, and means operable by said braking mechanism for simultaneously rendering the first-mentioned means functionally inoperative and for rendering said second means functionally operative.

4. In a device of the kind described and in combination, an electric signal mounted on a motor vehicle, a pair of circuits in parallel to said signal, a contact member in one of said circuits and operably connected to the 75 drive shaft of the vehicle, said contact member having an interrupted contact surface, a stationary contact for the other circuit spaced from said driven contact, a plurality of contacts carried by the brake rod 80 of the vehicle and movable therewith, one of said brake rod contacts engageable with said driven contact, and one of said brake rod contacts engageable with said stationary contact, whereby when said brake rod 85 is actuated one of its contacts will disengage from said stationary contacts to break the circuit thereof and one of said brake rod contacts will move into the path of said driven contact to successively make and break the 90 circuit controlled thereby.

5. In a device of the kind described and in combination, an electric signal mounted on a motor vehicle, a pair of circuits in parallel to said signal, means for completely breaking each of said circuits and for breaking one of said circuits intermittently, said means including a plurality of contacts, a brake rod, said contacts mounted on said brake rod and movable therewith, said contacts in said parallel circuits, and means for engaging certain of said contacts in one of said circuits intermittently when said brake rode is actuated, whereby when said brake rod is actuated one of said circuits is completely broken and the 105 other of said circuits is intermittently broken.

6. In a device of the kind described and in combination, an electric signal mounted on a motor vehicle, a plurality of circuits in parallel to said signal, a plurality of contacts 110 carried by the brake rod of said vehicle and movable therewith, said contacts in said parallel circuits, and means including said contacts for intermittently making and breaking one of said circuits when said brake rod is operated and simultaneously breaking all other circuits.

In testimony whereof, I have hereunto signed my name.

CLAUDE L. POST.
